UNITED STATES PATENT OFFICE

2,646,305

FULCRUM GRAB

Christian Andreas Sonderstrup, Maywood, Ill.,
assignor to Rada Products Company, a corporation of Illinois

Application December 8, 1949, Serial No. 131,853

8 Claims. (Cl. 294—67)

1

This invention relates to a material handling device and more particularly to a device for grabbing and holding sheet, strapped or bundled stock of relatively heavy material.

A general object of this invention is to provide a new and improved material handling device of the character described.

Another object is the provision of a device of the character described having a longitudinal axis of symmetry and means for positively attaching a hoist hook for lifting said device over the center of gravity thereof.

Another object is the provision of a material handling device having a grab hook pivoted to each longitudinal side of a frame in such a manner that a load supported by said hooks provides a component force tending to move the hooks about their pivot points toward the load.

Another object is to provide a material handling device having a grab hook pivotally mounted on each longitudinal side of a frame with the pivot points of said hook being selectively movable with respect to the frame to permit the hook to pick up material of different widths.

A further object is the provision of a material handling device of the character described having stabilizing hooks mounted on the ends of the frame at selective distances therefrom for grasping the load carried by the device to prevent the load from slipping off the device.

Other objects and features of the device will be apparent from the following description of an embodiment thereof illustrated in the accompanying drawings, in which:

Fig. 1 is a perspective view of the material handling device of this invention supporting a load shown in dotted outline;

Fig. 2 is a plan view of the device showing the grab hooks in dotted outline as placed in their outer position;

Fig. 3 is a cross section of a portion of the device taken substantially along line 3—3 of Fig. 2;

Fig. 4 is a side elevation of the device of this invention;

Fig. 5 is an end view of the device illustrated in the previous figures showing one of the grab hooks in dotted outline swung to its upper limited position; and

Fig. 6 is a fragmentary view of one of the tie bars showing a pivot pin of one of the grab hook arms therein and in dotted outline the same pivot pin in another position therein.

While there is shown in the drawings and hereinafter described in detail a preferred form of the invention, it is to be understood that the invention is not limited to the particular form and

arrangement shown. It is contemplated that various changes may be made by those skilled in the art without departing from the spirit and scope of the invention as defined in the appended claims.

Relatively heavy sheets, strapped or bundled stock are usually handled by the use of a crane or hoist, such cranes and hoists generally having a hoisting cable or chain and a hook on the lower end of the cable. Various means have been devised for gripping the stock or attaching the stock to the hook of the hoist in order to lift and transport the same. This invention is concerned with a grab adapted to grasp and hold relatively heavy stock and comprises generally a frame to which the hoist hook is attached and a pair of grab hooks, each mounted on an opposite side of the frame, said hooks being pivoted to the frame and depending therefrom to grab opposite sides of a load in order that the hoist may lift the same. The particular construction of the device ensures that each of the grab hooks once grasping a bundle of material or other load will not release the load until an operator so desires. Also in handling relatively long sheets or bundled stock there is a tendency for the load to slip out of the grab hooks if the grab is not placed at the precise center of the load. The material handling device of this invention is also provided with means for retaining the load on the grab hooks regardless of the placement of the load on the hooks.

The frame of the material handling device is symmetrical about its longitudinal axis and has a center supporting member 10 and a cross member 11 mounted on each end of the center supporting member 10. Referring to Fig. 1, the center supporting member 10 comprises two channels 12 placed back to back so that the legs 13 of each channel extend outwardly from the center of the frame. The channels 12 are in close contact at their ends and are separated at their center point by a plate 14. The hoist cable 15 passes through a sheave 16 having a hoist hook 17 at its lower end. The plate 14 has an eye 18 therein adapted to receive the hoist hook 17 so that the material handling device may be lifted and transported by the hoist from place to place. Since the device is symmetrical about its longitudinal axis it is important that the hoist hook 17 lifts the device at a point substantially over its center of gravity. The eye 18 in the plate 14 has an upper portion 19 shaped like an inverted V (as shown in Fig. 3) so that the hoist hook 17 will always come to rest at the top of the eye 18 thus ensuring that the device will be lifted substantially over its center of gravity.

On each end of the center supporting member 12 is a cross member or tie bar 20 positioned normal to the longitudinal axis of the center member. Each tie bar has end portions which are free and unobstructed so that the grab hooks may be pivoted to these portions as hereinafter described.

In lifting heavy material it is important that the device used may be quick of operation and yet ensure a positive grasping of the material. This invention provides a grab hook 22 pivotally mounted on each side of the frame in such a manner that once the hooks grasp a load the load has a tendency to strengthen the grasping force of the hooks on the load. Each grab hook comprises a material lifting member 23 mounted on and extending between a pair of arms 24. The arms 24 are of a bell-crank shape and have at the upper end thereof, a pivot pin 25 rigidly fixed to the arm 24. The pivot pin extends through an aperture 26 in the tie bar 20 so that the grab hook may swing about its pivot. To strengthen the arms, a tie rod 29 extends between the arms above the material lifting members 23. In Fig. 1 the grab hooks 22 are illustrated as placed so that the pivot pins 25 extend through apertures 26 in the tie bars closely adjacent the center support member 12 of the frame. In this position the grab hooks may lift relatively narrow bundles of stock or sheet material.

Referring more particularly to Figs. 5 and 6, each tie bar 20 is provided with a pair of spaced pivot apertures 26 connected by a horizontal slot 27 smaller in width than the diameter of the apertures 26. The pivot pin 25 has a flat surface 28 which if aligned with one side of the slot 27 will permit the pivot pin to be moved from one of the apertures 26 to the other in each free end of the tie bars 20. The particular position of the grab hooks in order to effect the movement of the pivot pins from one aperture to another is illustrated in Fig. 5. When the arms 24 are in the position such that the material lifting member 23 depends below the frame of the device the pivot pin is in the position illustrated in the right hand portion of Fig. 5. If the grab hook is moved upwardly to the position shown in dotted lines in Fig. 5 the pivot pin then assumes the position illustrated in dotted lines shown in the center of Fig. 6 so that the pin may be moved between the pivot apertures. In this manner the grab hooks may be moved from the positions shown in solid lines in Fig. 2 to the position illustrated in dotted lines in Fig. 2.

As stated above the grab hooks are so constructed that a load placed thereon tends to strengthen the grasping effect of the hooks on the load. This is accomplished by providing the grab hooks with arms of a bell-crank shape. A stop detent 30 is mounted on each arm and has a portion extending outwardly above the tie bar 20. This stop detent 30 prevents the material lifting member 23 from swinging inwardly toward the center of the device past a point directly below the pivot pin on the upper end of its supporting arms 24. Thus any load applied to the material lifting members 23 must be transferred through the arms, the pivots, and the frame to the hoist hook and the load will provide a force on the material lifting members creating a moment about the pivot pins 25 tending to force the material lifting member toward the center of the device. The stop detent also provides a convenient means for aligning the flat side 28 of the pins 25 with the side of the slot 27, for when the

grab hook is pivoted to the position shown in dotted lines in Fig. 5, the stop detent again contacts the upper edge of the tie bar 20 and in this position, the pivot pins may be moved through the respective slots as desired.

The material lifting members 23 are generally of an angle iron construction and have an upwardly extending flange 23a which is attached to the depending end of the arms 24, and a flange 23b extending at right angles to the flange 23a. As more clearly seen in Figs. 2 and 4, the center portion of the flange 23b is cut away at 35 to leave a portion in the center of the flange which will not contact any load picked up by the grab hooks. Opposite the cut-out portion of the flange 23b is a small upwardly extending cut-out portion 36 in the upwardly extending flange 23a. In picking up a load of bundled or strapped stock or sheets which may be placed upon skids, the material lifting members 23 may be placed under the load and the cut-out portions will allow the member to straddle the straps or skids. The material for which the device is designed to lift is quite heavy so that the cut-away portions of the lifting member 23 greatly aid in quick and efficient handling and stacking of such material.

Material placed on skids or bundled or strapped stock is often stacked by workers so that a space is provided between each bundle by placing wedges between the bundles. As described above the cut-away portions of the material lifting members 23 allow the members to be placed under the material to be lifted, yet because of the particular placement of the wedges it may not be possible to grasp a bundle of material at its center point. In such instances the weight of the material being lifted will not be balanced in the device about the hoist grab but will tip longitudinally of the device in one direction or the other. To prevent unevenly lifted bundles from slipping longitudinally out of the grasp of the material lifting members, auxiliary hooks 40 are removably attached to the ends of the frame to stabilize the load within the grasp of the grab hooks. Each stabilizing hook comprises a bell-crank shaped arm 41 having a material hooking member 42 at one end thereof and a chain 43 connected to the other end of the arm for removably attaching the stabilizing hook to the frame of the handling device. A bracket 44 is provided at the elbow of each arm 41 to present a convenient hand hold for placing the stabilizing hooks in contact with the load. As loads vary in length the stabilizing hooks 40 may be placed at variable distances from the frame by grasping selective links of the chain 43 in the slot 45 provided in a bracket 46 mounted upon the end of the channel members 12 on each end of the frame. One stabilizing hook 40 is provided for each end of the material lifting device so that a bundle of material may be effectively grasped on four sides as diagrammatically illustrated in Fig. 1.

In lifting and handling relatively heavy materials it is often necessary to provide a means for guiding the material as transported by the hoist through doorways and in and about machinery in a plant. An operator having the material handling device of this invention attached to a hoist may easily guide the material lifted thereby by the use of handles 50 inserted in retaining collars 51 mounted on one opposite pair of arms at one end of the device as illustrated in Fig. 1. The primary use of the han-

dles 50 is for swinging the hooks into or out of engagement with the load. The handles 50 are removable from the retaining collars 51 so that they may be dispensed with if the operator wishes.

From the foregoing description it is believed apparent that the invention provides a new and improved material handling device which ensures a positive grasping of material lifted through the action of the grab hooks utilizing the weight of the load to increase the grasping effect of the hooks. Also I have provided novel means for ensuring that a load grasped by the device will not slip longitudinally out of the grasp of the material lifting members and a device easily and quickly adaptable to handle various size loads.

I claim:

1. A material handling device comprising, a frame symmetrical about a longitudinal axis and having a center supporting channel and a tie bar attached to each end thereof normal thereto, said tie bars each having a pair of spaced pivot apertures connected by a slot smaller in width than the diameter of said apertures, a pair of grab hooks each mounted on an opposite side of said frame each comprising, a pair of bell-crank shaped arms, a material lifting member extending between and attached to the lower end of the arms, a pivot pin attached to the upper end of each arm and extending through one of said pivot apertures for pivotally mounting each arm respectively to a tie bar, said pivot pins having a flat side permitting said pin to be moved through said slot between said pivot apertures.

2. A material handling device comprising, a frame symmetrical about a longitudinal axis and having a center supporting member and a tie bar attached to each end thereof normal thereto, a grab hook mounted on each side of said frame comprising, a pair of bell-crank shaped arms pivotally mounted at their upper end respectively on said tie bars and a material lifting member extending between and attached to the lower ends of said arms, said tie bars each having a pair of spaced pivot apertures connected by a horizontal slot smaller than the diameter of said apertures, a pivot pin having one flat side extending through one of said pivot apertures for pivotally mounting each arm to a tie bar, and a stop detent attached to each arm and adapted to bear against the top of said tie bars for limiting the movement of said grab hooks past a point directly below said pivot in one direction and for aligning the flat side of said pivot with said slot when said arms are moved in the other direction to a position with said stop detent again contacting the top of the tie bars.

3. A material handling device comprising, a frame symmetrical about a longitudinal axis and having a center supporting channel and a tie bar rigidly attached at each end thereof normal thereto, a grab hook mounted on each longitudinal side of said frame and comprising, a pair of bell-crank shaped arms pivoted at their upper end respectively to said tie bars, and a material lifting member having an upstanding flange portion extending between and attached to the lower end of said arms and a foot portion extending from said flange portion toward the center of the device, said foot portion being

cut away in the center thereof to permit the foot portion to be placed under material resting on skids.

5 4. A material handling device comprising, a frame having a center supporting member and a tie bar mounted on each end of said center member, a pair of grab hooks mounted on opposite sides of said frame, said hooks being movable with respect to each other for grasping material of different widths, and a stabilizing hook adjustably attached to an end of said frame for grasping the material to prevent slipping thereof longitudinally out of the grip of said grab hooks.

10 5. A material handling device as claimed in claim 4 wherein a stabilizing hook is removably attached to each end of said frame.

15 6. A material handling device comprising, a frame having a center supporting member and a tie bar mounted on each end of said center member, a grab hook mounted on each longitudinal side of said frame, said hooks being pivotally mounted on said frame for movement with respect to each other for grasping material of different widths, and a pair of stabilizing hooks removably attached to each end of said frame, said hooks each having a hook arm and a chain attached to one end of the arm, said frame having means at each end thereof for grasping said chain at a selected link thereof whereby said stabilizing hooks may be removably fastened to the frame at selected distances therefrom.

20 7. A material handling device comprising, a frame symmetrical about a longitudinal axis and having a center supporting channel, a tie bar rigidly attached to each end of said channel normal thereto, a pair of grab hooks each mounted on an opposite side of said frame each comprising, a pair of bell-crank shaped arms, a material lifting member extending between and attached to the lower end of the arms, pivot means swingably securing the upper end of each arm to one of said tie bars, including cooperating parts in the form of a stud and aperture, one part being on the arm and a plurality of the other part being on the tie bar in spaced relation therealong, and means for selectively positioning said pivot means at a plurality of points along said tie bars for moving said grab hooks relative to said longitudinal axis.

25 8. A material handling device comprising, a frame symmetrical about a longitudinal axis and having a center supporting channel, a tie bar rigidly attached to each end of said channel normal thereto with said tie bars being parallel, a pair of grab hooks each mounted on an opposite longitudinal side of said frame each comprising, a pair of bell-crank shaped arms, a material lifting member extending between and attached to the lower ends of the arms, a pivot stud secured to the upper end of each arm, said tie bars each having a plurality of apertures adapted to receive said studs for swingably mounting said grab hooks on the frame, and means for selectively positioning said studs in said apertures for moving said grab hooks relative to said longitudinal axis.
